UNITED STATES PATENT OFFICE

2,243,005

TUBE CLEANER MOTOR

Paul E. Good, Riverton, N. J.

Application November 22, 1938, Serial No. 241,858

20 Claims. (Cl. 121—34)

This invention relates to tube cleaner motors and the like, and is an improvement upon the construction shown in my copending applications Serial Numbers 16,719, filed April 16, 1935, for "Rotary motor," 155,809, filed July 26, 1937, for "Tube cleaner motor," now patents numbered 2,141,982 and 2,154,328, respectively; and 224,395, filed August 11, 1938, for "Tube cleaner motor."

The motors of such prior applications comprise a spirally grooved cylinder and a shaft bearing rotatable pistons for coaction with the grooves of the cylinder.

Important objects of the present invention are the elimination of exhaust through the cylinder of the motor in the sense of directly exhausting the fluid pressure from the grooves of the cylinder to the exterior of the cylinder itself; the provision of a motor chamber readily converted from simple to compound by the mere substitution of one shaft for another therein; the provision of a construction which will permit the use of tube cutters which operate reversely to one another and which accordingly, materially reduce the rotative effort exerted upon the motor through the cutter action; the provision of means in a motor of this type in which the shaft is rotating for positioning the pistons during periods of disuse of the motor; the use of a construction in which a governor is readily incorporated and the provision of an arrangement facilitating assembly and repair of the device.

These and other objects I attain by the construction shown in the accompanying drawings wherein, for the purpose of illustration, I have shown a preferred embodiment of my invention and wherein:

Fig. 1 is a longitudinal sectional view through a motor constructed in accordance with my invention;

Fig. 2 is an elevation of the shaft of the motor of Fig. 1;

Fig. 3 is an illustration of a shaft body showing a construction providing multi-stage operation;

Fig. 4 is a sectional view similar to that of Fig. 1 but showing a modified form of motor incorporating a governor and adapted for the use of two oppositely rotating cutters;

Fig. 5 is an elevation of the shaft assembly of Fig. 4;

Fig. 6 is a shaft body interchangeably useable with that shown in Fig. 5;

Figs. 7, 8, 9, 10, 11 and 12 are characteristic sections through the shafts of the motors as indicated by the section lines on Figs. 1 to 6;

Fig. 13 is a section on line 13—13 of Fig. 4;

Figs. 14, 15 and 16 are characteristic sections on lines 14—14, 15—15, and 16—16 of Figs. 1 or 4;

Fig. 17 is a typical end elevation of the motor; and

Fig. 18 is a fragmentary side elevation of the cylinder showing the exhaust ports.

Referring now to the drawings, and more particularly to Figures 1 to 10 thereof, the numeral 10 generally designates a stationary casing having provision at one end for the introduction of fluid pressure thereto, as generally indicated at 11. Within this casing a shaft 12 is rotatably supported in bearings 13 and 14, and surrounding the shaft is a cylinder 15, likewise rotatably supported by the shaft and operating between thrust abutments 16 interposed between the cylinder and the casing. Cylinder 15 has internally arranged circumferential bands of spiral grooves 17 adapted for coaction with the lobes 18 of rotatable piston elements 19 supported in a slot 20 formed in the shaft. Shaft 12 comprises the inner body element 21 in which the diametral slot 20 is formed, such body element, at opposite sides being grooved for the passage of pressure and exhaust fluids.

The grooving at each side of the slot may comprise simply an intake groove 22 and an exhaust groove 23, as shown in Figs. 2 and 5 to 10, or may, as shown in Figure 3, comprise an intake groove 22a, an intermediate groove 24, and an exhaust groove 23a, the purpose of which will presently appear. In either instance the body member is surrounded by a sleeve 25 having an intake port 26 for each groove series and an exhaust port 27 for each groove series, these ports registering respectively with the leading and trailing portions of the grooves of the series with which they are associated to extents which may be best determined by the conditions under which the motor is to operate, and acting in effect after the manner of the control valves of the ordinary steam engine.

Where sleeve 25 is applied to the body member 21 of Fig. 2, all of the intake ports 26 will communicate with the intake grooves 22 of the body member and all of the exhaust ports 27 will communicate with the exhaust grooves 23 thereof. When applied to the body member 21a of Figure 3, the intake port 26 adjacent the inlet end alone communicates with the groove 22a while the remaining intake ports communicate with the intermediate groove 24. Similarly, the initial exhaust port 27, or that nearest the intake end, communicates with the intermediate

groove, while the remaining exhaust ports communicate with the exhaust grooves 23a.

Thus, with the shaft body of Figure 2, the engine is a simple expansion engine, the fluid after expansion in the grooves being directly conducted to the exhaust, while in the form shown in Figure 3, the fluid received in the initial set of grooves is conducted by the intermediate groove of the body to the remaining groove series of the cylinder for further expansion therein before delivery to the exhaust providing a compound motor. Since the shafts, as will be obvious from a comparison of these figures, are freely interchangeable, the motor may, at will, be transformed from simple to compound, or vice versa.

The sleeve has slots 28 for the passage of the lobes of the pistons located in the diametral slot 29, and within the slot 29 are arranged spring-pressed followers 29 which engage the pistons and constantly urge them outwardly when the shaft is at rest. When, as in the present instance the shaft rotates, the centrifugal effort of these followers moves them radially outwardly so that they disengage the pistons 19 which at that time will have considerable centrifugal effort of their own which will serve to insure their proper engagement in the slots of the cylinder. However, as pointed out in the prior applications above identified, the direction of rotation of the pistons will usually be made such that the gyroscopic effort thereof resulting from their rotation about their own centers and about the axis of shaft 12 will cause a gripping between the pistons, reducing such effort to a considerable extent and thereby preventing undue wear between the pistons and the walls of the cylinder grooves. The walls of the slot 29 are preferably provided with hardened steel or composition inserts 30 against which the pistons seat during rotation thereof.

Bearing 13 is held against the intake end of shaft 12 by a collar 31 having an extension 32 threaded into the adjacent tubular end of the shaft and the shaft, inwardly of this collar, has ports 33 communicating with the intake grooves 22 or 22a as the case may be. Seated upon the periphery of the intake end of the shaft against the bearing 13 is a bevel gear 34 against which the adjacent end of the sleeve 25 abuts. The opposite end of this sleeve is abutted by a collar 35 threaded on the shaft end 36. The shaft end is projected and threaded or otherwise adapted, as at 36a, for the application of a cutter. The thrust element 16 engaging the outer end of cylinder 15, is spaced from the adjacent end of the casing, thus providing an annular chamber 37 from which outlet ports 38 are formed in the end casing wall. The end exhaust port 27 is elongated so that its outer end communicates with the annular chamber 37, in a manner hereinafter described.

The casing 10 is formed in three sections, of which the central section comprises an annular ring 39 having threaded engagement with the end sections. This annular ring mounts a plurality of bevel gears 40 which mesh with the gear 34 and with a gear 41 formed on the end of the cylinder. It will be obvious that during operation of the motor, the casing 10 being stationary, the cylinder and shaft will rotate reversely so that for a given speed of the shaft 12 the capacity of the motor is doubled as regards its capacity were the cylinder 15 stationary.

Since both the cylinder and shaft rotate, it is

obviously possible to utilize both in the operation of cutters. The cylinder 15 has a sleeve-like extension 42 surrounding the exhaust end of shaft 12, such extension having a circumferential series 5 of ports 43 for communication with the annular chamber 37 of casing 10. The outer end of the extension 42 has a reduced portion forming the bearing 14 for the reduced end portion 36 of shaft 12. The reduced portion 44 of cylinder 15 10 is adapted at 47 for the reception of a cutter 48, while the end 36 of shaft 12 is provided with cutter 50 of slightly less diameter than the cutter 48.

As in the construction illustrated in my co-pending application, Serial No. 224,395, for "Tube cleaner motor," the inner end of the slot in the shaft body is closed by a removable plug P to prevent incoming air from passage into this slot. When this plug is removed, the spring-pressed followers 29 may, likewise, be removed, following which the rotary pistons 19 may be moved into the confines of the shaft and the shaft bodily withdrawn from the cylinder.

In Figures 4, 5, 6 and 13, I have illustrated a modification of the structure of the remaining figures to enable incorporation of a governor G.

The applied governor is substantially identical with that described in my copending application Serial No. 155,809 above identified, now Patent No. 2,154,328. In applying the governor, the shaft is provided with a head 51, the inner face of which is formed with an annular channel 52 communicating with the hollow forward end 53 of the shaft and thus, through the ports 33, with the intake grooves 22 or 22a of the shaft body. Head 51 abuts removable head 54 for casing 10a through a thrust bearing 55. Head 51 at its inner end forms a seat for the gear 34a corresponding directly to the gear 34 and against which the sleeve 25a abuts. This head is formed in two sections detachably connected and constructed to provide mounts for radially disposed thimbles 56 having ports 57 communicating with the annular passageway 52. The interiors of these thimbles are open and communicate with the hollow interior of the head which is, in turn, in communication with the intake fitting 58 of the motor. The removable plug P' employed in this structure has a head P² which interiorly fits the head 51 between groove 52 and the open inner ends of the thimbles. The plug P' is removable, as in the case of plug P. Slidable in these thimbles are valves 59 which are constantly urged inwardly by springs 60. When in the innermost position, 55 ports in these valves align with the ports 57 of the thimbles 56 and, obviously, as the speed of the motor increases and the valves move outwardly by centrifugal force, the amount of air entering the motor chamber will be constantly reduced until it is finally a minimum.

It will be obvious that in this type of construction when two cutters are employed the opposite rotation of the cutters will minimize or altogether counteract the torque reaction upon the motor as a result of the cutting operation, thus relieving the operator of considerable strain in holding the same. It will also be obvious that in this type of construction, where desired, a single cutter applied to either the shaft or cylinder may be utilized.

Obviously, the construction principles employed in the above illustrations, while disclosed as for use in motors, may be readily adapted for use as compressors or pumps, and since considerable change is otherwise possible in the general struc-

ture without departing from the spirit of my invention, I do not wish to be understood as limiting myself to the particular forms illustrated except as hereinafter claimed.

I claim:

1. In a tube cleaner motor, oppositely rotating cylinder and piston bearing shaft elements, and a cutter for and driven by each element.

2. In a rotary motor or the like, concentric relatively rotatable cylinder and shaft elements, the outer element comprising the cylinder and being provided on its inner surface with a circumferential series of spiral grooves, means to introduce fluid pressure to said grooves and exhaust fluid pressure therefrom, the shaft fitting within the cylinder, rotatable pistons carried by said shaft and having lobes meshing with said grooves and blocking said grooves from end to end during their passage therethrough, the shaft having a slot in which the body portions of the pistons are disposed, and gearing connecting said shaft and cylinder whereby the shaft and cylinder are reversely rotated.

3. In a rotary motor or the like, relatively rotatable cylinder and shaft elements, the outer element comprising the cylinder and being provided on its inner surface with a circumferential series of spiral grooves, means to introduce fluid pressure to said grooves and exhaust fluid pressure therefrom, the shaft fitting within the cylinder, rotatable pistons carried by said shaft and having lobes meshing with said grooves and blocking said grooves from end to end during their passage therethrough, the shaft having a slot in which the body portions of the pistons are disposed, the inner portions of the piston elements being in confronting overlapping relation, said piston elements rotating in opposite directions upon relative rotation of said inner and outer members, and gearing connecting said shaft and cylinder whereby the shaft and cylinder are reversely rotated.

4. In a rotary motor or the like, a rotating shaft element, a rotatable cylinder element, said cylinder having in its surface a plurality of circumferential series of spiral grooves and said shaft mounting rotatable pistons for each groove series having lobes blocking said grooves from end to end as the elements are relatively rotated, said shaft comprising a body portion having intermediate its ends a series of grooves comprising supply grooves and exhaust grooves and further having a slot mounting said pistons, and sleeve means sealingly engaged with the ends of the body portion and the surface of the body portion between said grooves and between said grooves and slots, said sleeve means having slots for the passage of the lobes of said pistons and having ports formed therein, said ports comprising supply ports for the delivery of pressure to the grooves of the cylinder from the supply grooves of the shaft and exhaust ports communicating with the grooves of the cylinder for the exhaust of pressure fluid from the grooves of the cylinder to the exhaust grooves of the shaft.

5. In a rotary motor or the like, a rotating shaft element, a rotatable cylinder element, said cylinder having in its surface a plurality of longitudinally spaced series of spiral grooves and said shaft mounting rotatable pistons having lobes blocking said grooves of each series from end to end as the elements are relatively rotated, said shaft comprising a body portion having intermediate its ends a plurality of grooves comprising supply grooves, exhaust grooves and intermediate

grooves and further having a slot mounting said pistons, sleeve means sealingly engaged with the ends of the body portion with the surface of the body portion between said grooves and between said grooves and slots, said sleeve means having slots for the passage of the lobes of said pistons and supply ports for the delivery of pressure to the grooves of one of the groove series of the cylinder communicating with said supply grooves, exhaust ports communicating with the grooves of said series for the exhaust of pressure fluid from the grooves thereof to said intermediate grooves, supply ports for supplying fluid from the intermediate grooves to the remaining groove series of the cylinder and exhaust ports for conducting fluid from the grooves of said remaining groove series of the cylinder to the exhaust grooves of the shaft.

6. In a rotary motor or the like, a rotating shaft element, a rotatable cylinder element, said cylinder having in its surface a plurality of circumferential series of spiral grooves and said shaft mounting rotatable pistons for each groove series having lobes blocking said grooves from end to end as the elements are relatively rotated, said shaft having a series of passages comprising intake and exhaust passages and having ports formed therein, said ports comprising supply ports for delivery of pressure to the grooves of the cylinder from the supply passages of the shaft and exhaust ports communicating with the grooves of the cylinder for the exhaust of fluid pressure from the grooves of the cylinder to the exhaust passages of the shaft.

7. In a rotary motor or the like, a rotating shaft element, a rotatable cylinder element, said cylinder having in its surface a plurality of circumferential series of spiral grooves and said shaft mounting rotatable pistons for each groove series having lobes blocking said grooves from end to end as the elements are relatively rotated, said shaft having a series of passages comprising intake passages, exhaust passages, and intermediate passages, and further having ports, said ports comprising supply ports for the delivery of pressure to the grooves of one of the groove series of the cylinder from the intake passages of the shaft, exhaust ports communicating with the grooves of said series for the exhaust of fluid pressure from the grooves thereof to said intermediate passages, supply ports for supplying fluid from the intermediate passages to the remaining groove series of the cylinder and exhaust ports for conducting fluid from the grooves of said remaining groove series of the cylinder to the exhaust passages of the shaft.

8. The device of claim 4 wherein a pair of interchangeable shafts is provided and interchanging of the shafts converts the motor from simple to compound.

9. In a tube cleaner motor, oppositely rotating cylinder and piston bearing shaft elements, a cutter for and driven by each element, and a governor controlling the speed of the shaft.

10. In a rotary motor or the like, concentric relatively rotatable cylinder and shaft elements, the outer element comprising the cylinder and being provided on its inner surface with a circumferential series of spiral grooves, means to introduce fluid pressure to said grooves and exhaust fluid pressure therefrom, the shaft fitting within the cylinder and having a slot, rotatable pistons carried by said shaft and partially disposed in said slot and having lobes meshing with said grooves and blocking said grooves from end

to end during their passage therethrough, and spring-pressed followers holding said pistons in extended position.

11. In a rotary motor or the like, concentric relatively rotatable cylinder and shaft elements, the outer element comprising the cylinder and being provided on its inner surface with a circumferential series of spiral grooves, means to introduce fluid pressure to said grooves and exhaust fluid pressure therefrom, the shaft fitting within the cylinder and having a slot, rotatable pistons carried by said shaft and partially disposed in said slot and having lobes meshing with said grooves and blocking said grooves from end to end during their passage therethrough, and spring-pressed followers holding said pistons in extended position, said slot opening through an end of said shaft to permit removal of said followers, said pistons having a diameter such that they may be positioned within the confines of the shaft when said followers are removed.

12. In a rotary motor or the like, concentric relatively rotatable cylinder and shaft elements, the outer element comprising the cylinder and being provided on its inner surface with a circumferential series of spiral grooves, means to introduce fluid pressure to said grooves and exhaust fluid pressure therefrom, the shaft fitting within the cylinder and having a slot, rotatable pistons carried by said shaft and partially disposed in said slot and having lobes meshing with said grooves and blocking said grooves from end to end during their passage therethrough, and spring-pressed followers holding said pistons in extended position, said slot opening through an end of said shaft to permit removal of said followers, said pistons having a diameter such that they may be positioned within the confines of the shaft when said followers are removed, a removable plug closing the slot at said end of the shaft.

13. A motor comprising reversely rotatable cylinder and piston-bearing shaft elements and a stationary casing element, a cutter driven by each of said cylinder and shaft and geared connections between said cylinder, casing and shaft elements whereby the relative speeds of the cylinder and shaft exceed the speed of either cutter.

14. A motor comprising reversely rotatable cylinder and piston-bearing shaft elements and a stationary casing element, a cutter driven by each of said cylinder and shaft, geared connections between said cylinder, casing and shaft elements whereby the relative speeds of the cylinder and shaft exceed the speed of either cutter, and a governor controlling the relative speeds of the shaft and cylinder.

15. In a rotary motor or the like relatively rotatable cylinder and shaft elements, geared connections between said cylinder and shaft elements whereby they are reversely rotated, a member continuously driven by each of said elements during operation of the motor, said cylinder having in its surface a plurality of circumferential series of spiral grooves and said shaft elements mounting rotatable pistons for each groove series having lobes blocking said

grooves from end to end as the elements are relatively rotated, said shaft elements being two in number, one of said shafts having ports for delivery of fluid pressure from a suitable source to each of the groove series of said cylinder and exhaust ports for the exhaust of fluid pressure therefrom, the other of the shafts having intake ports for the delivery of fluid pressure from said source to the ports of the first of the groove series and transfer ports for transferring fluid pressure from the preceding groove series to a succeeding groove series, the last of the groove series being in communication with exhaust ports for the exhaust of fluid pressure therefrom, said shafts being interchangeable whereby to convert the motor from simple to compound.

16. In a rotary motor or the like relatively rotatable cylinder and shaft elements, geared connections between said cylinder and shaft elements whereby they are reversely rotated, a member continuously driven by each of said elements during operation of the motor, said cylinder having in its surface a plurality of circumferential series of spiral grooves and said shaft elements mounting rotatable pistons for each groove series having lobes blocking said grooves from end to end as the elements are relatively rotated, said shaft elements being two in number, one of said shafts having ports for delivery of fluid pressure from a suitable source to each of the groove series of said cylinder and exhaust ports for the exhaust of fluid pressure therefrom, the other of the shafts having intake ports for the delivery of fluid pressure from said source to the ports of the first of the groove series and transfer ports for transferring fluid pressure from the preceding groove series to a succeeding groove series, the last of the groove series being in communication with exhaust ports for the exhaust of fluid pressure therefrom, said shafts being interchangeable whereby to convert the motor from simple to compound.

17. In a tube cleaner motor oppositely rotating cylinder and piston-bearing shaft elements, a cutter for and driven by each element and a stationary casing concentric with and surrounding said elements.

18. The device of claim 17 wherein the casing includes gears operating upon stationary pivots and coacting with gears carried by the cylinder and shaft elements whereby to insure reverse rotation of said elements.

19. In a tube cleaner motor oppositely rotating piston bearing shaft and cylinder elements, a cutter for and driven by each element, a governor controlling the relative speeds of the shaft and cylinder and a stationary casing concentric with the shaft and cylinder and housing the same.

20. The device of claim 19 wherein the casing includes gears operating upon stationary pivots and coacting with gears carried by the cylinder and shaft elements whereby to insure reverse rotation of said elements.
